UNITED STATES PATENT OFFICE.

OTTO FOX, OF LAKewood, OHIO, ASSIGNOR TO THE BRYANT HEATER AND MANUFACTURING COMPANY, OF CLEVELAND, OHIO, A CORPORATION OF OHIO.

WATER HEATER.

Application filed March 28, 1928. Serial No. 18,987.

This invention relates to boilers or water heaters such as are employed in connection with hot water storage tanks and with the heating plants of dwellings and other buildings. Boilers of the type referred to above, in so far as the water conveying portions are concerned, are generally formed of a series of parallel cast iron sections provided with front and rear upright conduit portions which are connected together by transverse ducts. These sections are connected together at the top and bottom by inlet and outlet headers or manifolds, the inlet header being arranged at the bottom and the outlet header at the top, and one being on the front side and the other on the rear side of the boiler.

Generally the transverse ducts of adjacent sections are staggered so that the flame and heated gases in passing from the burners to the outlet pipe or stack are baffled to an extent by the overlapping portions of the ducts of adjacent sections so as to take tortuous passageways in passing upward, and thereby have a good heating action on the water in the ducts.

A very good example of boiler or water heater constructed as above, is illustrated in my prior Patent No. 1,025,389, granted May 7, 1912.

The principal object of the present invention is to provide an efficient boiler of this general type wherein the cast iron sections or elements are similar, but are formed so that the ducts of adjacent sections overlap each other as with the staggered arrangement of ducts which requires two different castings in forming the adjacent sections.

In accordance with the present invention, the ducts are made asymmetrical so that the upper portions of the ducts of one section will overlap the lower portions of the ducts of the adjacent section or sections, and to render this arrangement highly efficient in action, and more particularly to prevent the heated air and products of combustion from crowding to one side of the boiler by passing diagonally upward and laterally, the ducts of the different sections, particularly the lowermost ducts are connected by webs which serve to compel the heated air to pass in the desired tortuous paths upwardly between the sections.

The invention may be further briefly summarized as consisting in certain novel details

of construction, and combinations and arrangements of parts which will be described in the specification and set forth in the appended claims.

In the accompanying sheets of drawings wherein I have shown the preferred embodiment of the invention, Fig. 1 is a front view of the boiler partly in section along the line 1—1 of Fig. 2; and Fig. 2 is a transverse vertical sectional view with the section taken between two of the adjacent sections or elements of the boiler.

Referring now to the drawings, the boiler may have any suitable base 10 which generally carries a number of burners 11 to which gas may be supplied by a pipe 12.

The water-conveying portion of the boiler consists of a number of similar parallel cast iron sections 13, which are connected together at the bottom and in this instance on the rear side by an inlet header or manifold 14, and at the top and in this instance at the front by an outlet header or manifold 15. The sides of the boiler are provided with side plates 16 and at the top there is a so-called flue top 18 adapted to be provided with an outlet 19 for the products of combustion. At the front the spaces between the sections 13 are closed by removable panels 20, but at the rear the sections fit closely together. It is to be understood that in practice the entire boiler is enclosed in a cover, usually of sheet metal and asbestos, but the same is not shown, as my invention does not reside in these parts.

Referring now to the sections 13, it will be noted that each section is composed of upright conduit portions 13^a and 13^b, located at the front and rear sides respectively of the section, and slightly inclined transverse ducts 13^c connecting the conduit portions. It may be here stated that the number of ducts 13^c, and therefore the height of the sections will depend upon the required capacity, and therefore the number may be greater than here shown. It is to be noted that portions of the ducts of one section overlap the ducts of the adjacent section or sections, and in order that the sections may all consist of similar castings, formed from one pattern, the overlapping of adjacent ducts is obtained by making the ducts asymmetrical, and in this instance, substantially Z-shaped, with the upper and lower portions

of the ducts of each section extended laterally a sufficient distance so that when the sections are assembled side by side, the upper portions of the ducts of one section, which portions project in one direction, will overlap the oppositely projecting lower portions of the ducts of the adjoining section. The above described shape of ducts and the overlapping arrangement may be utilized for all the ducts of the different sections, but I find that better results are obtained by shortening the laterally extending portions of the bottom row of ducts, as indicated in Fig. 1, so that they do not overlap, these ducts being designated 13^a.

The asymmetric or Z-shape gives the ducts a more or less general inclination upwardly and to the right, as the ducts are viewed in Fig. 1, and as a consequence there would be a tendency, if there were open spaces between the superimposed ducts of each section, for the hot air and products of combustion to have an upward and lateral flow crosswise of the boiler in the direction of this general inclination, so as to crowd the heat to one side, rendering the burners on such side relatively ineffective and resulting in a non-uniform heating action in the different sections. To avoid this lateral flow through or between the superimposed ducts of the different sections, the ducts of each section are joined by webs 13^a, thus closing the otherwise open spaces. It is not essential that these webs be employed between all the ducts of the different sections, as I may omit them between the two uppermost ducts of each section. It is important, however, that they be employed between adjacent lower ducts.

With the arrangement above described, the heated air and products of combustion are required to take zigzag paths uniformly between all the different sections, or between the outermost sections and the side covers 16 the latter being preferably provided with inwardly extending wings or flanges 16^a projecting between the ducts of the sections adjacent thereto.

With the above arrangement the heat comes in direct contact with all portions of all the ducts of the different sections in the zigzag courses upward, there being no dead spaces, especially as the ducts are designed with this asymmetrical or zigzag construction everywhere with inclined surfaces.

While I have shown the preferred construction, I do not desire to be confined to the exact details shown, and particularly to the exact illustrated shape of the ducts, but aim in my claims to cover all modifications which do not involve a departure from the spirit and scope of my invention as defined in the appended claims.

Having described my invention, I claim:

1. A boiler or water heater composed of

a series of sections arranged side by side, each section having front and rear conduit portions and spaced transverse ducts communicating at their ends with the conduit portions, the walls of the ducts between their ends being joined one to another and the ducts having on opposite sides of a vertical section longitudinally disposed lateral extensions, those on one side being formed on the upper portions of the ducts and those on the other side being formed on the lower portions of the ducts, the ducts of the adjacent sections being spaced to provide passageways for heated gases.

2. A boiler or water heater composed of a series of sections arranged side by side, each section having front and rear conduit portions and superposed transverse ducts extending between them, the walls of adjacent superposed ducts of each section being joined between the conduit portions and the ducts of adjacent sections having overlapping extensions, the extensions running longitudinally of the ducts on both sides of each section, those on one side being formed on the lower portions of the ducts and those on the other side being formed on the upper portions of the ducts, the ducts of the adjacent sections being spaced to provide passageways for heated gases.

3. A boiler or water heater composed of a series of sections arranged side by side each section having front and rear conduit portions and a continuous wall extending between them, the wall being formed with a plurality of superposed ducts which communicate at their ends with the conduit portions and are formed on opposite sides with lateral extensions which are disposed longitudinally of the ducts and overlap the extensions of the ducts of the adjacent section or sections, the duct extensions on one side of a section being formed on the lower portions of the ducts and those on the other side being formed on the upper portions of the ducts, the ducts of the adjacent sections being spaced to provide passageways for heated gases.

4. A boiler or water heater composed of a series of similar sections arranged side by side and composed of front and rear upright conduit portions joined by transverse substantially Z-shaped ducts, the said ducts of the adjacent sections being spaced to provide passageways for heated gases, the ducts of one section overlapping ducts of the adjoining section or sections, and at least the lowermost ducts of the different sections being joined by webs.

5. A boiler or water heater composed of a series of sections arranged side by side, each section comprising front and rear conduit portions, spaced transverse ducts connecting the same and continuous webs closing the spaces between the ducts, the said

ducts of the adjacent sections being spaced to provide passageways for heated gases, each duct having laterally inclined side walls and oppositely extending lateral projections at the upper and lower ends thereof, the extensions of the ducts of one section extending between projections of ducts of adjacent sections to form tortuous passageways between the sections, the lowermost ducts having side walls more nearly vertical than the ducts above the same to provide a freer passageway for gases between them.

6. A boiler or water heater composed of a series of similar sections arranged side by side and composed of front and rear upright conduit portions joined by transverse substantially Z-shaped ducts, the said ducts of the adjacent sections being spaced to provide passageways for heated gases, the ducts of one section being horizontally aligned with ducts of the adjoining section or sections and having projecting portions which overlap to form tortuous passageways between

the sections, the ducts of each section being joined by webs.

7. A boiler or water heater composed of a series of sections arranged side by side, each section comprising front and rear conduit portions with vertically arranged spaced transverse ducts connecting the same and continuous webs closing the spaces between the ducts, the ducts being hollow and substantially Z-shaped, thereby providing hollow staggered projections which with respect to the projections of adjacent ducts in adjacent sections are partially overlapping, thereby providing tortuous passageways between the sections, the lower ducts of each section having shorter projections to thereby provide wider spaces between transversely adjacent ducts than the spaces between ducts above the same.

In testimony whereof, I hereunto affix my signature.

OTTO FOX.
